US00D862570S

(12) **United States Design Patent** (10) Patent No.: **US D862,570 S**
(45) Date of Patent: ** Oct. 8, 2019

(54) **GOGGLES**(71) Applicant: **H&H Sports Protection SRL**, Pistoia (IT)(72) Inventor: **Massimiliano Frosi**, Soresina (IT)(73) Assignee: **H&H Sports Protection SRL**, Pistoia (IT)(***) Term: **15 Years**(21) Appl. No.: **29/616,244**(22) Filed: **Sep. 5, 2017****Related U.S. Application Data**

(62) Division of application No. 35/500,308, filed on Nov. 6, 2015 (U.S. filing date under 35 U.S.C. 384), and having an international filing date of Nov. 6, 2015, now Pat. No. Des. 800,825.

(51) **LOC (12) Cl.** ..... **16-06**(52) **U.S. Cl.**USPC ..... **D16/313**(58) **Field of Classification Search**

(57) **CLAIM**

The ornamental design for goggles, as shown and described.

DESCRIPTION

FIG. 1 is a front elevation view of googles showing the new design;

FIG. 2 is a perspective view thereof;

FIG. 3 is a left side view thereof;

FIG. 4 is a right side view thereof;

FIG. 5 is a bottom plan view thereof;

FIG. 6 is a top plan view thereof; and,

FIG. 7 is a back elevation view thereof.

The "JUST1" symbol forming part of the claimed design is a registered trademark of H&H Sports Protection.

1 Claim, 7 Drawing Sheets(56)
